US0D1001997S

(12) **United States Design Patent** (10) **Patent No.:** **US D1,001,997 S**
(45) **Date of Patent:** **** Oct. 17, 2023**

(54) **DEVICE FOR NASAL SPRAY**

(71) Applicant: **APTAR FRANCES SAS**, Le Neubourg (FR)

(72) Inventor: **Lila Graine**, Beynes (FR)

(**) Term: **15 Years**

(21) Appl. No.: **35/512,269**

(22) Filed: **Jul. 12, 2021**

(80) **Hague Agreement Data**

Int. Filing Date: **Jul. 12, 2021**

Int. Reg. No.: **DM/215414**

Int. Reg. Date: **Jul. 12, 2021**

Int. Reg. Pub. Date: **Jul. 30, 2021**

(30) **Foreign Application Priority Data**

Feb. 15, 2021 (EM) 008435770-0001

(51) **LOC (14) Cl.** **29-02**

(52) **U.S. Cl.**

USPC **D24/110**

(58) **Field of Classification Search**

USPC ..... D24/110, 164, 190, 200, 210, 211, 215, D24/216, 110.5; D13/168; D9/724, 561 CPC . A61M 15/08; A61M 2205/276; G09B 23/28; G09B 19/24

Primary Examiner — Mojtaba Tehrani

(57) **CLAIM**

The ornamental design for a device for nasal spray, as shown and described.

DESCRIPTION

1. Device for nasal spray

1.1: Perspective

1.2 : Front

1.3 : Back

1.4 : Right

1.5 : Left

1.6 : Top

The broken lines in the drawings disclose the unclaimed portions of the device for nasal spray only and form no part of the claimed design.

1 Claim, 6 Drawing Sheets
